(57) **CLAIM**

We claim the ornamental design for a pendant for sexual stimulation, as shown and described.

DESCRIPTION

FIG. 1 is an isometric view, from the back left, of the pendant for sexual stimulation; and,

FIG. 2 is an elevation view of the front of the pendant for sexual stimulation;

FIG. 3 is an elevation view of the right side of the pendant for sexual stimulation;

FIG. 4 is an elevation view of the back of the pendant for sexual stimulation;

FIG. 5 is an elevation view of the left side of the pendant for sexual stimulation;

FIG. 6 is a plan view of the top of the pendant for sexual stimulation; and,

FIG. 7 is a plan view of the bottom of the pendant for sexual stimulation.

The broken line disclosures are understood to be for illustrative purposes only and forms no part of the claimed design.
